TORPEDO

John Hays Hammond, Jr., Gloucester, Mass.

Application January 5, 1934, Serial No. 705,353

11 Claims.

(Cl. 114—21)

This invention relates to ordnance devices and more particularly to torpedoes.

According to one form of the invention, a torpedo may be provided with a light sensitive device which controls the detonation of the explosive charge thereof when it passes beneath a ship. The torpedo mechanism may include a photoelectric cell which is energized by the light of day transmitted through the water above the 5 torpedo. When the torpedo passes beneath the ship, the shadow causes the deenergization of the photoelectric cell which in turn may be arranged to cause the detonation of the war head.

As most modern warships are provided on their 15 sides with so called "blisters" which make the explosion of a torpedo ineffective, it has been found necessary to detonate the torpedoes beneath the center of a ship and in contact with the hull at this point. In order to accomplish 20 this result it is necessary to run the torpedoes at a depth several feet deeper than the draft of the ship being attacked. Passage of the torpedoes beneath the ship will thus be assured in spite of the unevenness of the torpedo's run, the 25 variable draft of the enemy ship according to loading and the effect of a seaway upon the torpedo.

The invention may also provide a means 30 whereby the detonation of the war head of the torpedo is delayed a predetermined time after the photosensitive means has passed into the shadow of the ship in order to allow the explosion to occur near the central portion of the vessel, where it would be most effective. As it 35 is well known that the effect of an explosion under water drops off exceedingly rapidly with increase of depth, the invention may provide means for causing the torpedo to be steered sharply upward, as soon as the light sensitive 40 arrangement has passed into the shadow of the ship, thus causing the explosion to occur in close proximity to the hull of the enemy vessel.

This invention also consists in certain new 45 and original features of construction and combinations of parts hereinafter set forth and claimed.

Although the novel features which are believed 50 to be characteristic of this invention will be particularly pointed out in the claims appended hereto, the invention itself, as to its objects and advantages, the mode of its operation and the manner of its organization may be better understood by referring to the following description taken in connection with the accompanying 55 drawings forming a part thereof, in which:

Figure 1 represents diagrammatically the forward portion of a torpedo provided with invention.

Figure 2 represents diagrammatically the afterbody of the same torpedo, and

Figure 3 diagrammatically illustrates the course of a torpedo attacking an enemy vessel.

Like reference characters denote like parts of the several figures of the drawings.

In the following description and in the claims parts will be identified by specific names for convenience, but they are intended to be generic in their application to similar parts the art will permit.

Referring to the accompanying drawings, more particularly to Figures 1 and 2, there is shown a water-borne body such as a carrier for explosives having a water tight torpedo hull and arranged to be propelled in the usual manner by propellers 10 located at the after end. The hull 9 is provided with two transverse bulkheads 11 and 12, thus providing two compartments 13 and 14, the former being filled with an explosive charge 15, such for example as T. N. T.

A hole is provided in the hull 9 at the center of the compartment 14. This hole is covered by a sheet of glass or other transparent material 16. Mounted in a tube 17 is a lens 18 which is positioned directly below the hole in the hull. The interior of the tube 17 is painted a black so as not to reflect any light. Positioned at the focus of the lens 18 is a photoelectric cell 19 which is connected in the input circuit of an amplifier 20.

A clock-work mechanism 21 is provided which drives a commutator 22. This commutator is provided with a conducting segment 23. To the shaft of the commutator is secured an arm 24 which normally engages a pin 26. A second arm 27 is provided for limiting the motion of arm 24 and the commutator 22.

Engaging the commutator 22 are four brushes 28, 29, 30 and 31. The brush 28 is connected to one side of the output circuit of the amplifier 20. The brush 29 is connected to one side of a solenoid 32 and to one side of a relay 33, the other side of which is connected to the other side of the amplifier 20 and to the other side of the solenoid 32.

The solenoid 32 is provided with a core which is adapted to be moved to the left as shown in Figure 1 when this solenoid is energized. At one end of this core is a piston 37 which reciprocates in a cylinder 38. This cylinder

ed with a port 38 covered by a flap valve 39 which is adapted to allow the air to escape from this cylinder. The cylinder is also ed with a port 41 the opening in which is lled by a needle valve 42 for restricting the air through this port.

The other end of the core 36 is secured an ing member 45 between which and the d 32 is mounted a compression spring 46. ed on the insulating member 45 is a contact 47 which is connected to the contact 31 and able times engages a contact 48 mounted insulating base 49. The contact 48 is ted to one side of a detonator 50, the side of which is connected to the contact 31 through a battery 51. The back contact of ay 33 is connected through a battery 150 side of a solenoid 151 located in the after f the torpedo as shown in Fig. 2. The ide of the winding of this solenoid is con through a switch 152 to the contact 47. ucting segment 152 is provided in the in block 48 and is connected to the arming relay 39.

core of the solenoid 151 normally engages 52 which is mounted for reciprocation in a casing 53 which forms part of the end cylinder 54. This cylinder communicates e interior of the valve by means of a port o communicating with the interior of the a pipe 55 which is supplied with fluid pressure from any suitable source (not

Slidably mounted in the cylinder 54 ton 57 which is operatively connected to 58 which is pivoted for rotation about 59 supported by the shell of the torpedo. orpedo is provided with the usual ver horizontal rudders 61 and 62. The lat operated by means of a link 63 from the al steering engine 64 which is supplied id under pressure from a pipe 65 and is ed by a valve 66 operated in a well-known from the depth mechanism 67. Secured nk 63 is a collar 68 which is located in of travel of the arm 58.

automatically starting the clock-work sm 21 a heavy weight 71 is secured to of a flat spring 72 the upper end of fastened to the casing of the clock-work sm 21. The weight 71 is provided with a n 73 which normally engages a finger 74 controls the starting of the clock-work sm. Engaging the end of the finger 74 ig 75 which is supported on a bracket 78. operation of this system when the torred the inertia of the weight 71 causes moved backward relative to the torr disengaging the projection 73 from the which is moved upwardly under the acce spring 76 thus causing the clock-work sm to start turning the commutator 22 determined speed. Switch 152 is closed ring. The circuit through the solenoid be open, however, as the brush 47 does contact with the segment 153. After a nined interval of time the segment 23 mmutator 22 will engage the brushes 23 us connecting the amplifier 20 to the 32 and the relay 33 both of which will zed, as the photoelectric cell will by this receiving the light of day, focused upon ns of the lens 18. This will cause the of the solenoid 32 to be moved rapidly it as the air in the cylinder 38 is freely d through the port 39. The contact 47

moves off of the segment 48 thus keeping the circuit to the detonator 50 open as the segment 23 comes into engagement with brushes 30 and 31. The solenoid 151 will still remain deenergized due to the opening of its circuit by the relay 33.

This condition continues as long as the photoelectric cell 18 receives light through the lens 18. When the torpedo passes beneath an enemy ship, however, the light will be cut off from the photoelectric cell 18 thus causing the deenergization of the relay 33 and the solenoid 32. The former action closes the circuit through the sole noid 151 as the contact 47 is then in engagement with the segment 153. This causes the core of this solenoid to be moved to the right thus releasing the valve 52 which is moved upwardly under the action of a spring surrounding this valve which allows the fluid under pressure to pass from the pipe 55 through the port 53 to the interior of the cylinder 54. This causes the piston 57 to be moved to the left, thus rotating the arm 58 in a counter-clockwise direction. This arm engages the collar 68 and forces it together with the link 63 to the left against the action of the steering engine 64 thus throwing the horizontal rudders 52 into the hard-up position which causes the torpedo to be steered sharply upward.

The deenergization of the solenoid 32 allows the core 36 to be moved slowly to the right under the action of the spring 46, the speed of this motion being determined by the setting of the needle valve 42. After the predetermined interval of time the contact 47 will engage the segment 48 thus closing a circuit from the battery 51 through the segment 23 and contact 47 to the detonator 50 which is detonated thereby exploding the charge of explosive 15 in the war head of the torpedo.

This explosion will take place directly under the center of the ship and in contact with the hull as the mechanism has been so timed that it will give the torpedo a sufficient time to reach a position under the center of the ship and the horizontal rudders will have directed the torpedo upwardly so that it is in contact with the hull of the ship.

If it is desired to operate the system without the use of the horizontal rudders the switch 152 may be opened thereby causing the solenoid 151 to remain inoperative so that the horizontal rudders will not be affected.

Fig. 3 shows a torpedo of this construction attacking the enemy's ship. In this figure the enemy vessel is pictured at 81 and 3 positions of the torpedo at 82, 83 and 84 respectively. In the position shown at 82 the torpedo is running submerged at the required depth and the photoelectric cell is energized by light received through the water. At 83 the torpedo is shown entering the shadow 85 of the hull of the vessel 81. At this instant the illumination of the photoelectric cell has been shut off and the operation of the horizontal rudder just described has been initiated causing the torpedo to follow the course indicated by the dotted line 86 until it reaches the position shown at 84 when the explosive charge will be detonated directly under the center of the ship and in contact with the hull thereof thus insuring the destruction of the enemy vessel.

In order to prevent the premature explosion of the torpedo in the event that it should pass under some floating debris and thereby momen-

tarily occult the light sensitive means, any type of well-known delay action circuit may be incorporated in the amplifier 20, so as to make it necessary for the photoelectric cell 19 to be occulted for an appreciable length of time before the operation of the mechanism will be initiated.

An important advantage of this system of running torpedoes at considerably greater depths than are now used is the fact that at these depths the wakes are much farther behind the torpedoes when they come to the surface due to the longer time it takes the bubbles of air to rise to the surface and that the wakes are much less conspicuous due to the fact that the air has had a longer time to become diffused in the water. It is, therefore, much more difficult to observe and locate these torpedoes than those run at present day depths.

The photoelectric cell 19 may be of the new type in which the amplifier 20 may be replaced by a sensitive relay, which controls the circuits of the solenoid 32 and the relay 33. These new cells generate sufficient current to operate a sensitive relay directly without the use of an amplifier or a battery. A condenser may be shunted across the relay or any other well-known device may be employed to delay the operation of the relay, so that the mechanism will not be operated by a momentary occultation of the photoelectric cell, such as would be caused by the torpedo passing under floating debris.

It is well understood that instead of a photoelectric cell other devices can be specified operating on different parts of the spectrum. It would be possible to substitute in place of the photoelectric cell 19 a bolometer or other heat sensitive device which would function due to the variation of temperature.

Although only a few of the various forms in which this invention may be embodied have been shown herein, it is to be understood that the invention is not limited to any specific construction, but might be embodied in various forms without departing from the spirit of the invention or the scope of the appended claims.

What is claimed is:

1. In combination with a moving body, an explosive charge carried thereby, a means for exploding said charge, a solenoid for controlling said means so that when said solenoid is deenergized it will cause the explosion of said charge and a light receptive device which, when illuminated from an external source, causes said solenoid to be energized and when not illuminated causes said solenoid to be deenergized.

2. In a moving body, an explosive charge, means for detonating said charge, a light sensitive device for operating said detonating means so that when the illumination on said device is changed it will cause the detonation of said explosive charge and means for preventing the detonation of said explosive charge for a predetermined time after the illumination on the light sensitive device has been changed.

3. In combination with a moving body, a explosive charge, means for causing the detonation of said charge and light sensitive means including a delay device, for controlling said detonating means so that at a predetermined interval after the intensity of illumination of said light sensitive means is changed it will cause the detonation of said explosive charge.

4. In an underwater torpedo, rudders for controlling the vertical movement thereof, a light sensitive device controlled by natural light transmitted directly through the water for operating said rudders so that when the illumination of said device is changed it will cause said torpedo to be directed upwardly.

5. In an underwater torpedo, means for controlling the course of said torpedo, means mounted on said torpedo for receiving visible light transmitted directly through the water from an external source, and means operated by said last means for changing the course of said torpedo.

6. The method of maneuvering a torpedo which comprises firing the torpedo, steering said torpedo underneath an enemy ship, directing said torpedo against the hull beneath the center of said ship, and detonating said torpedo prior to contact with the ship.

7. The method of maneuvering a torpedo which comprises firing the torpedo so that it will pass under an enemy ship, utilizing the shadow of said ship to deflect said torpedo upwardly and to detonate said torpedo beneath said ship.

8. The method of maneuvering a torpedo which comprises firing the torpedo so that it will pass under an enemy ship, causing the shadow of said ship to deflect said torpedo upwardly and initiate the detonation of the explosive charge in said torpedo and delaying the detonation of said explosive charge for a predetermined length of time.

9. The method of maneuvering a submarine torpedo which comprises causing said torpedo to follow an underwater path and steering said torpedo by variations in the natural light transmitted directly through the water adjacent said torpedo.

10. In a torpedo, means to cause said torpedo to travel through the water at a depth below the draft of the target ship and means operable by the shadow of the ship when the torpedo passes thereunder for re-directing said torpedo upwardly toward the bottom of said ship.

11. In a torpedo, means for causing said torpedo to travel through the water at a depth greater than the draft of the target ship, means carried by said torpedo for receiving radiations from an external source transmitted directly through the water thereto and means operated by variation of said radiation caused by the shadow of a ship when the torpedo passes thereunder for re-directing the torpedo upwardly toward the bottom of said ship.
